CLAIM

The ornamental design for arcade machine, as shown and described.

DESCRIPTION

FIG. 1 is top front right isometric view showing a first arcade machine of the invention.

FIG. 2 is front view showing the arcade machine of FIG. 1.

FIG. 3 is a rear view showing the arcade machine of FIG. 1.

FIG. 4 is a right side view showing the arcade machine of FIG. 1.

FIG. 5 is a left side view showing the arcade machine of FIG. 1.

FIG. 6 is a top view showing the arcade machine of FIG. 1.

FIG. 7 is a bottom view showing the arcade machine of FIG. 1.

FIG. 8 is top front right isometric view showing a second arcade machine of the invention.

FIG. 9 is front view showing the arcade machine of FIG. 8.

FIG. 10 is a rear view showing the arcade machine of FIG. 8.

FIG. 11 is a right side view showing the arcade machine of FIG. 8.

FIG. 12 is a left side view showing the arcade machine of FIG. 8.

FIG. 13 is a top view showing the arcade machine of FIG. 8; and,

FIG. 14 is a bottom view showing the arcade machine of FIG. 8.

The broken lines in the drawings depict portions of the arcade machine that form no part of the invention.
